HIS ATTORNEY

UNITED STATES PATENT OFFICE.

PAUL BERMAN, OF WILMINGTON, DELAWARE.

ASH SIFTER.

Application filed May 2, 1922. Serial No. 557,842.

To all whom it may concern:

Be it known that I, PAUL BERMAN, a citizen of the United States, residing at Wilmington, in the county of New Castle and 5 State of Delaware, have invented certain new and useful Improvements in Ash Sifters, of which the following is a specification.

This invention relates to an improved sifter and more particularly to one in the 10 form of a scoop or shovel adapted for sifting ashes or other materials.

It is an object of the invention to provide a device of the above character which may be economically manufactured and 15 which is so constructed that the material to be sifted may be readily taken up and will, upon rocking or tilting the device, cause the ashes or other material to move over a reticulated bottom so that the dust may be 20 readily separated from the cinders or other large particles.

These objects, and other advantageous ends which will be described hereinafter, I attain in the following manner, reference 25 being had to the accompanying drawings in which—

Figure 1 is a plan view of the device,

Figure 2 is a side elevation,

Figure 3 is a vertical longitudinal sectional view taken on the line 3—3 of Figure 30 1, and

Figure 4 is a transverse vertical sectional view taken on the line 4—4 of Figure 2.

Referring to the drawings, the improved 35 sifting device is shown in the form of a scoop or shovel consisting of a body 5 produced from a sheet metal blank having a comparatively wide central portion and sides converging toward each end. The blank is 40 folded, as indicated at 6 on a longitudinal line substantially midway of the width of the blank and the ends bent toward each other thereby producing a U-shaped element having a rear wall 7 and side walls 8, the 45 walls being composed of two layers of metal. The side walls and bottom edges of the side walls thereof incline, from rear to front, in the direction of the upper edge.

A bottom 9 of wire mesh, or other reticulated material, is secured to the body 5 by 50 means of an upturned edge 10 extending between the edges of the double wall and held by rivets 11, extending through the three thicknesses of material.

To support the front edge of the meshed 55 bottom, I provide a strip 12 of sheet metal

of substantially rectangular shape. This strip is folded upon itself and its ends 13 bent at a right angle. The front edge of the meshed bottom is folded inwardly and 60 between the two walls formed by the strip and the upturned edges of the metal strip are secured between the ends of the body portion 5 by rivets 14 taking through the five thicknesses of material and the bottom is further secured in the folded strip by rivets 15 taking through the three thicknesses of material. If desired, the inner 65 bottom edge of the wall may be bent inwardly forming a flange 16 to reinforce the inner 70 edges of the meshed bottom. The body portion will be provided with a suitable handle socket 17 which preferably extends upwardly as well as rearwardly.

This construction produces a sifter with 75 open front and with walls comparatively high at the rear and low at the front. The sifter may be placed in the ash pit to receive the ashes or it may be forced into the ashes, or other material, like a shovel. When 80 shaking, the bottom will be inclined upwardly so that it will serve as a front wall and the material will gravitate downwardly toward the rear of the sifter. As the material is agitated by forward and backward 85 oscillation a thorough separation of the fine from the coarser particles is effected.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended 90 claims.

Having thus described my invention, what I claim as new and desire to secure by Letters Patent is:—

1. A sifting device comprising a body wall open at the front and extending perpendicularly to its top edge, and a reticulated bottom inclined from the rear toward the top edge of the body.

2. An ash sifting device in the form of a scoop or shovel comprising a body having vertical sides and back and open at the front, and a sifting bottom, the body being disposed substantially at right angles to the top edge thereof and in acute-angled relation to the bottom edge thereof.

3. An ash sifting device in the form of a scoop or shovel comprising a body having sides and a back and open at the front; a sifting bottom for the body, said body being disposed at right angles to the top edge thereof and in acute-angled relation to the bottom edge thereof, and a reinforcing strip at the forward edge of the bottom and between the sides of the body.
- 10 4. An ash sifter or the like comprising a body formed of a comparatively wide central portion and sides converging toward the ends, said blank being folded on a longitudinal line substantially midway of the width of the blank and the ends bent toward each other to produce a U-shaped element having a rear wall and side walls composed of two layers of material; a sifting bottom having an upturned edge secured between the layers of said folded blank; a folded strip having its ends secured between said layers at the forward portions of the side walls and having the forward edge of the bottom secured between its folded portions, 20 and a handle secured to the back of the body.
- 15 5. An ash sifter or the like comprising a body formed of a substantially lenticular shaped blank folded on a median line between its apexes; a sifting bottom having an 25 upturned edge secured between the sides of

said folded blank; a folded strip also secured between said folded side at the open front portion of the body and having the forward edge of the bottom secured thereto, the sides of the body tapering forwardly and the back 35 of the body being disposed at a forward inclination, said body enlarging toward its open end and tapering toward its upper edge at the back, and a handle receiving socket attached to and extending upwardly 40 from the back portion whereby the body may be rocked on the bottom edge thereof at the back.

6. A sifter shovel consisting of a blank folded to form a double wall with the ends bent toward each other to form a U-shaped element; a reticulated bottom conforming to the shape of the element and having an upturned edge secured between said walls, and a folded strip secured on the front edge 45 portion of the bottom having upturned edges also secured between said walls.

In testimony whereof I have signed my name to this specification in the presence of two subscribing witnesses.

PAUL BERMAN.
